ROTARY DRILLING MACHINE

Richard R. Bloss, Beaumont, Tex., assignor to The International Derrick & Equipment Company of Texas, Beaumont, Tex., a corporation of Texas

Application May 24, 1940, Serial No. 336,937

15 Claims. (Cl. 255—23)

This invention relates to a rotary drilling machine.

The invention embodies certain improvements over that type of rotary drilling machine disclosed 5 in my co-pending application filed in the United States Patent Office on the 5th day of June, 1939, under Serial No. 277,459.

An object of the invention is to provide a rotary drilling machine embodying a base structure and 10 a table rotatably mounted therein, said base structure having extended ends whose top surfaces are approximately flush with the top surface of the table but decline from the table and are curved transversely. These top surfaces are 15 so shaped in order that the drilling fluid discharged onto the same will quickly and effectively drain off so as not to interfere with the workmen who at times stand on the extended ends of the base while carrying on drilling operations.

20 As is well known while breaking up a drill stem, in withdrawing the same from a well, the drilling fluid filling the stem will drain out over the rotary drilling machine. This drilling fluid is very slippery and if the top surfaces of the base structure 25 are flat this slippery, or slimy, drilling fluid will remain thereon and will form a constant hazard to the workmen. Accordingly, the surfaces referred to are given only sufficient pitch and curvature to cause the efficient draining of the drilling fluid therefrom and at the same time to form 30 a safe support for the workmen standing thereon.

It is another object of the invention to provide a rotary drilling machine, the rotary table of which is provided with radial scrapers which are 35 effective to carry off the mud or other foreign matter which may find its way between the base structure and table and to discharge the same through suitable openings provided for the purpose in the outer sides of the base structure.

40 It is a further object of the invention to provide novel sealing means between the rotary table and the base structure which is very effective to exclude foreign matter from the interior of the machine.

45 With the above and other objects in view the invention has particular relation to certain novel features of construction, operation and arrangement of parts, an example of which is given in this specification and illustrated in the accompanying drawings:

Figure 1 shows a perspective view of the complete machine.

Figure 2 shows a perspective view as viewed 55 from the bottom.

Figure 3 shows a longitudinal, sectional view taken on the line 3—3 of Figure 1.

Figure 4 shows an enlarged, fragmentary, longitudinal sectional view.

60 Figure 5 shows an enlarged, fragmentary,

transverse, sectional view taken on the line 5—5 of Figure 4.

Figure 6 shows an enlarged, fragmentary, longitudinal, sectional view taken on the line 3—3 of Figure 1.

Figure 7 shows an enlarged, fragmentary, horizontal, sectional view, taken on the line 7—7 of Figure 6, and

Figures 8, 9, and 10 show fragmentary, vertical, sectional views illustrating other types of guard 10 ring employed.

Referring now more particularly to the drawings wherein like numerals of reference designate the same parts in each of the figures, the numeral 1 designates the base structure as a whole which 15 is of an inverted box-like form having the side walls 2, 2, the end walls 3, 4 and the top indicated generally by the numeral 5. The lower margins of the walls 2, 2 terminate in the skids or runners 6, 6 whose forward ends are upwardly turned as 20 more accurately shown in Figures 1 and 2.

The top has a circular opening 7 of somewhat greater diameter than the width of the base, said opening being defined on each side by the laterally arched hoods 8, 8. The opening 7 is defined 25 by a vertical wall circular in horizontal cross-section designated generally by the numeral 9. The lower end of this wall is reduced in diameter, forming, by such reduction, a horizontally extending annular ledge 10 which has an annular, 30 inside, upstanding rim 11 shown more clearly in Figure 3 and the wall extends upwardly and is outwardly offset forming the intermediate, annular ledge 12 as shown in Figure 3 and near its upper end is again outwardly offset defining the 35 opening 7, said last-mentioned offset portion defining a channel which merges into downwardly directed discharge openings 13 underneath the hoods 8, one on each side of the base structure as shown in Figure 2. Slush or other foreign 40 matter finding its way from the top of the table into said channel will be discharged out through the openings 13 as will be hereinafter explained.

The rim 11 and the outer wall forms an annular channel within the wall of which the ledge 10 forms the bottom. The circular wall 9 is anchored in place by the transverse and radial, vertically extended webs 14, 15 which are formed integrally with said wall, the web 14 being formed integrally with the side walls 2 and the web 15 being formed integrally with the end wall 4 all of which is shown more accurately in Figure 2.

Between the end wall 3 of the base and the circular wall 9 and formed integrally with said walls there is a circular shell 16 forming a housing, the 55 inner end of which is enlarged and formed into a gear case 16a. The housing is provided with drain outlets 17, 17a closed by suitable plugs as shown in Figure 3.

The base consisting of the parts hereinabove 60

described is preferably cast as a single unit.

The numeral 18 designates the rotary table as a whole. It is mounted in the opening 7 with its upper surface substantially flush with the adjacent part of the upper surface of the top 5 of the base. It will be noted from an inspection of Figures 1 and 4 that the top surface 5 of the base extends each way beyond the rotary table thus providing the walking spaces 5a, 5b at each end for workmen. These extensions 5a, 5b decline each way from the rotary table and are upwardly curved or arched transversely so that the slippery drilling fluid which is spilled out of the drill stem as it is broken up and which falls on the base structure will readily drain off so that said extensions will automatically keep themselves relatively clean and free of slippery substances to the end that workmen standing on the top of the base structure will not be liable to fall thus minimizing the danger of injury to them. To facilitate this drainage longitudinal and cross-channels may be provided as shown in Figures 5, 8, 9 and 10.

Around the opening 7 the top of the base is countersunk and the adjacent margin of the table is also countersunk thus providing an annular groove to receive the annular table guard ring 19 which breaks the joint between the table and the top of the base and wards off much of the slush and other foreign matter which might enter between the table and the base top. An annular inside groove 20 is thus provided in which the margin of the rotary table runs and which merges, at each side of the base, into the discharge openings 13 as hereinabove explained. The margin of the table is provided with external, radial lugs 21 spaced apart therearound and forming scrapers. They may be cast integrally with the rim of the table or otherwise secured thereto. They rotate with the table and carry the mud or other foreign matter which may collect in the channel 20 around to the openings 13 through which said foreign matter drops to the outside of the rotary.

Upstanding from and formed integrally with the defining wall 9 there is an annular flange 22 shown more clearly in Figure 6 and the margin of the table has an annular groove 23 which faces downwardly and which receives the flange 22. Within and fitting closely against the inner wall of the flange 22 there is a suitable outwardly expansible seal ring which is seated in a circular groove in the rotary table as clearly shown in Figure 6. The seal ring 24 may be locked against rotation with the table by means of the lug 22a on the flange 22 which fits between the open ends of the seal ring. Around and fitting closely against the outer wall of the flange 22 there is a seal ring 25 which is seated in a circular groove 60 in the rotary table as clearly shown in Figure 6 and which may be locked against rotation with the table by means of the lug 22b on the flange 22 which fits between the open ends of said seal ring 25. A very efficient seal is thus provided to exclude foreign matter that may find its way between the outer margin of the rotary table and the guard ring 19.

The rotary table has the usual central opening for the drill pipe which is surrounded by a depending skirt 26. It will be noted from an inspection of Figure 3 that the lower end of the skirt is reduced in diameter and fitted snugly within the reduced lower end of the wall 9. The reduction of the lower end of said skirt provides the external, annular, downwardly facing bear-

ing face 27 about the skirt of the table against which there is fitted and secured the upper raceway ring 28 which surrounds the skirt. On the ledge 10 within the wall 9 there is the raceway ring 29. The rings 28, 29 have the opposing complementary raceways 30, 31 therein in which the series of ball bearings 32 are confined and which support the table 18. There is an annular hold-down ring 33 supported on and anchored to the upper ledge 12 of the wall 9 and which is preferably formed of two sections for ease in assembly.

The inner margin of the holdown rings overlaps an external, annular flange 34 on the table, said ring and flange forming an upthrust bearing to maintain the table securely seated on the bearings 32 on which it is mounted.

The upper end of the opening through the table is enlarged and polygonal in shape thus providing an inside supporting seat 18a for the table bushing 35 which is mounted in the table and extends downwardly into the table skirt and is formed to receive conventional drive bushings for engaging and driving the kelly of the drill stem. The bushing 35 is formed of sections, two being shown.

Surrounding and suitably secured to the underside of the margin of the rotary table 18 there is a gear ring 36 formed with beveled gear teeth which are in mesh with a pinion 37 which is located in the case 16 and is fixed on the inner end of the pinion shaft 38. The shaft 38 may be driven from a suitable power through sprocket wheel 39 fixed on the outer end thereof.

Means have been provided for releasably locking the bushing 35 in place and other means have been provided for locking the rotary table against turning while making up and breaking out the drill stem; also, a novel type of assembly for mounting the pinion shaft and pinion has been provided as well as a novel lubricating system. These features, however, are substantially disclosed in my co-pending application hereinabove referred to and will not be further explained in detail herein.

In the illustration shown in Figure 8 the top surface of the guard ring 19a is shown sloping in the same plane as the top of the extension 5a. As illustrated in Figure 9 the top surface of the guard ring 19b is shown partly sloping in the same plane as the top of the extension 5a and partly on a level with the adjacent top surface of the table, while in Figure 10 the top surface of the guard ring 19c is shown flat, or on the level with the adjacent top surface of the rotary table. In each of these forms, however, the guard ring has the outwardly sloping mud drainage channels to drain off the mud and slush as well as the cross-channels to provide for drainage as well as to provide roughened upper surface to prevent slippage of the workmen.

What I claim is:

1. In a rotary drilling machine, the combination of a base having an outer, annular wall and a pinion shaft supporting portion extending outwardly from said wall, a rotary table located within said annular wall, the pinion shaft supporting portion being provided with an integrally formed upper surface which declines outwardly from the upper surface of the rotary table.

2. In a rotary drilling machine, the combination of a base having an outer, annular wall and a pinion shaft supporting portion extending outwardly from said wall, a rotary table located within said annular wall, the pinion shaft sup-

porting portion being provided with an integrally formed upper surface which declines outwardly from the upper surface of the rotary table and which is upwardly arched.

- 5 3. In a rotary drilling machine, the combination with a base having a vertical opening therethrough and an outer, annular flange, of a rotary table mounted in the opening within said flange, the base being provided with an outwardly 10 extended portion formed integrally with the base of substantially rectangular cross-section the upper surface of said outwardly extended portion declining outwardly from the plane of the upper surface of the rotary table.
- 15 4. In a rotary drilling machine, the combination with a base having a vertical opening therethrough and an outer, annular flange, of a rotary table mounted in the opening within said flange, the base being provided with an outwardly 20 extended portion formed integrally with the base of substantially rectangular cross-section, the upper surface of said outwardly extended portion declining outwardly from the plane of the upper surface of the rotary table and being upwardly 25 convexed.

5. In a rotary drilling machine, the combination of a base having an opening defined by a vertical, annular wall, a table rotatably supported in the base within the annular wall and having 30 its upper surface in substantially the same plane as the top of the wall, said base having integral extensions about each side of the opening and having vertical side walls and vertical end walls which define a box-like construction, the upper 35 margins of the end walls being parallel to, but below the plane of, the table top, said base also having an integral top extending from the upper portion of the annular wall to the end walls and side walls, said top being arched and declining 40 each way from said annular wall.

6. In a rotary drilling machine, a base of an inverted box-like construction having vertical side walls and vertical end walls and having an opening for a rotary table defined by a surrounding, annular wall whose upper end is above the upper margins of the end walls, a top for the base connecting the annular wall with the end walls, a portion of the top adjacent the annular wall being flush with the top of said annular wall 50 and the upper surface of the top declining from the annular wall and being upwardly curved.

7. In a rotary drilling machine, a base of an inverted, box-like construction having an upstanding, annular wall defining an opening, a table rotatably supported in the opening, the base having integral extensions on opposite ends, the upper surfaces of which decline from the upper end of the annular wall to the end walls of the base, said upper surface being upwardly 60 curved in cross-section.

8. In a rotary drilling machine, a base of an inverted, box-like construction having approximately vertical side walls and approximately vertical end walls, an annular wall defining a vertical opening through the base, a rotary table supported for rotation within the opening, said base having an upwardly curved top surface which declines outwardly from a plane which is substantially common with the plane of the upper 70 surface of the table.

9. In a rotary drilling machine, a base having an annular wall defining a vertical opening, a

table rotatably mounted in the opening, said base having an inwardly facing channel which receives the rim of the table and which has a discharge opening outside of the base, and external means on said rim provided to engage foreign matter in the channel and to carry said foreign matter to, and discharge the same through, said discharge opening.

10. In a rotary drilling machine, a base having a table receiving opening and having an inwardly facing, annular channel merging into oppositely arranged discharge openings outside of the base, a table rotatably mounted in the base opening and having a rim extending into the channel, external scrapers on the rim in the channel effective to carry foreign matter in the channel around to, and to discharge it through, said discharge openings.

11. In a rotary drilling machine, the combination including a base having an upstanding, annular wall defining an opening, a rotatably supported table in the opening having annular grooves, seal rings in said grooves in sealing relationship with the outer and inner surfaces, respectively, of the upstanding, annular wall.

12. In a rotary drilling machine, the combination including a base having an upstanding, annular wall defining an opening, a rotatably supported table in the opening having annular grooves, seal rings in said grooves in sealing relationship with the outer and inner surfaces, respectively, of the upstanding, annular wall and means for preventing rotation of the seal rings with the table.

13. In a rotary drilling machine, the combination of a base having an outer annular wall and a pinion shaft supporting portion extending outwardly from said wall, a rotary table located within the annular wall, the pinion shaft supporting portion being provided with an integrally formed upper surface which declines outwardly from the upper surface of the rotary table and a guard ring which covers the joint between the table and base and whose upper surface slopes downwardly and outwardly.

14. In a rotary drilling machine, the combination of a base having an outer annular wall and a pinion shaft supporting portion extending outwardly from said wall, a rotary table located within the annular wall, the pinion shaft supporting portion being provided with an integrally formed upper surface which declines outwardly from the upper surface of the rotary table and a guard ring which covers the joint between the table and base and whose upper surface slopes downwardly and outwardly and is provided with drainage channels.

15. In a rotary drilling machine, the combination of a base having a vertical opening therethrough and an outer, annular flange, of a rotary table mounted in the opening within said flange, the base being provided with an outwardly extended portion formed integrally with the base of substantially rectangular cross-section, the upper surface of said outwardly extended portion declining outwardly from the plane of the upper surface of the rotary table and being upwardly convexed and an annular guard ring covering the joint between the rotary table and the base and whose upper surface has outwardly and 70 downwardly declining drainage channels.

RICHARD R. BLOSS.
